UNITED STATES PATENT OFFICE.

GUSTAVE A. REINKE, OF WESTWOOD, CALIFORNIA.

RAKER GAUGE.

Application filed January 28, 1922. Serial No. 532,477.

To all whom it may concern:

Be it known that I, GUSTAVE A. REINKE, a citizen of the United States, residing at Westwood, in the county of Lassen, State of California, have invented certain new and useful Improvements in Raker Gauges; and I do declare the following to be a full, clear, and exact description of the same, reference being had to the accompanying drawings, 10 and to the characters of reference marked thereon, which form a part of this application.

This invention relates to improvements in raker gauges such as are used in saw sharpening operations, and is particularly an improvement over that type of gauge shown in my Patent No. 1373636, dated Apr. 5th, 1921.

The principal object of the present invention is to simplify the mechanism used in making the necessary adjustments, so as to make the device simpler and less expensive of construction than the type shown in the above mentioned patent, while not interfering in the slightest with the efficiency and accuracy of operation of the device.

These objects I accomplish by means of such structure and relative arrangement of parts as will appear by a perusal of the following specification and claims.

In the drawings similar characters of reference indicate corresponding parts in the several views.

Fig. 1 is a longitudinal elevation of one side of the device.

Fig. 2 is a similar view of the reverse side.

Fig. 3 is an enlarged cross section taken on the line 3—3 of Fig. 2, showing the adjusting mechanism.

Fig. 4 is a detached view of an adjustment plate and connected parts.

Referring now more particularly to the characters of reference on the drawings, the numeral 1 denotes a plate-frame having longitudinal and transverse pairs of plates 2 and 3, each pair being spaced at the top and bottom of the frame respectively and being to one side of the center of length of the frame.

The upper plates 2 are connected by a bridge 4 extending upwardly therefrom and forming a bearing for a threaded stem 5, which above the bridge is provided with a threaded portion 6, which is double the diameter and pitch of the portion 5, but has the threads cut in the same direction.

Above the portion 6 is a finger wheel 7 whereby to turn the stem, this wheel being adapted to be held at any point by means of a spring clip 8 adapted to engage the knurled edge of the wheel.

The lower end of the stem 5 terminates in a pin 9 seated on a leaf spring 10 supported by the plates 2. Depending from the spring in line with the stem 5 is a peg 11 which is adapted to project somewhat below the lower faces of the plates 2.

The threaded portion 6 is engaged by a block 12 provided with a substantially semi-circular tapped portion 12a. This block is connected by arms 13 to a transverse plate 14, positioned above the plates 3 and spanning the space therebetween, said plate 14 having a longitudinal slot 15 to receive the teeth of a saw therethrough.

The arm structure 13 and the plate connected thereto are allowed vertical movement on the frame 1 and are flexibly mounted thereon by means of a flat spring 16 bearing against the cross bar 13a of the arms 13, the spring being held in place and under tension by means of a set screw 17 secured in the frame 1.

Since the spring 16 is nearer the plate 14 than the upper block 12, additional means for positively holding the tapped block 12 in engagement with the stem 6 is had by means of another spring 18 bearing against the block, this spring being preferably formed as a part of the spring 8.

Of course the portion 6 of the stem could have the same diameter as the portion 5, with double the pitch, but such a pitch would be too great for such a small stem, or else the latter would have to be increased in size also, which would increase the total size and weight of the parts unnecessarily.

The functioning and purpose of the device is identical with what was fully set forth in the above mentioned patent, and need not be repeated in detail. It suffices to say that the object to be attained is to move the plate 14 to or from the plates 3 in the same relation and at the same rate of speed as the peg 11, so that when the plate 14 abuts against the plates 3, the peg 11 will at that time be in exact alignment with the under faces of the plates 2; and as the plate 14 moves away from the plates 3, the peg 12 will move a corresponding distance below the lower faces of the plates 2, both movements being had simultaneously by turning

the finger wheel 7 in one direction or the other.

This operation is carried out in the present case as follows: Suppose the wheel 7 to be turned to the right, or clockwise, and that the threaded portions 5 and 6 are cut right-hand. The spring 10 will then be depressed, forcing the peg 11 below the lower faces of the plates 2, since the stem 5 will 10 move downwardly in the bridge 4, which to all intents and purposes is a part of the frame 1, and could in fact be made integral therewith. At the same time the block 12 and plate 14 connected thereto is being 15 moved, but this movement takes place in the opposite direction, the extent of such upward movement being equal to the downward movement of the peg 11, by reason of the greater pitch threaded portion 6 on the 20 stem.

This upward movement of the plate equal to the downward movement of the stem and peg, or vice versa, is obtained, as will be evident, as long as one threaded portion is of 25 twice as great pitch as the other and there is no lost motion.

From the foregoing description it will be readily seen that I have produced such a device as substantially fulfills the objects of 30 the invention as set forth herein.

While this specification sets forth in detail the present and preferred construction of the device, still in practice such deviations from such detail may be resorted to as do 35 not form a departure from the spirit of the invention, as defined by the appended claims.

Having thus described my invention, what I claim as new and useful and desire to secure by Letters Patent, is:—

1. A raker gauge including a frame, transverse and spaced top and bottom plates, each pair of plates being in parallel alignment, a peg supported between the top 45 plates, a plate bridging the space between the lower plates and positioned thereabove and arranged for vertical movement, and a single turnable means operating both on the peg and the last named plate for moving

them an equal amount in opposite directions. 50

2. A raker gauge including a frame, transverse and spaced top and bottom plates, each pair of plates being in parallel alignment, a peg supported between the top 55 plates, a plate bridging the space between the lower plates and positioned thereabove and arranged for vertical movement, and a single turnable means operating both on the peg and the last named plate for moving 60 them, but in opposite directions.

3. A raker gauge including a frame, transverse and spaced top and bottom plates, each pair of plates being in parallel alignment, a peg supported between the top 65 plates, a plate bridging the space between the lower plates and positioned thereabove and arranged for vertical movement, a turnable stem provided with a threaded portion and threaded into the frame and arranged 70 to move the peg when rotated, there being another threaded portion on the stem, a member connected to the last named plate and engaged by the last named threaded portion, and means whereby as the stem and 75 peg move vertically in one direction the last named plate will be moved the same distance but in the opposite direction.

4. A raker gauge including a frame, transverse and spaced top and bottom plates, 80 each pair of plates being in parallel alignment, a peg supported between the top plates, a plate bridging the space between the lower plates and positioned thereabove and arranged for vertical movement, a turnable stem provided with a threaded portion 85 and threaded into the frame and arranged to move the peg when rotated, there being another threaded portion on the stem, a member connected to the last named plate 90 and engaged by the last named threaded portion, said last named threaded portion having double the pitch of the first named portion and the threads being cut in the same direction. 95

In testimony whereof I affix my signature.

GUSTAVE A. REINKE.
